(57) **CLAIM**

The ornamental design for a refrigerator, as shown and described.

DESCRIPTION

FIG. 1 is a perspective view of a refrigerator showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is an enlarged view of encircled portion 8 of FIG. 1. The broken lines illustrating portions of the refrigerator form no part of the claimed design.

The dot-dot-dash broken lines encircling enlargement portions of the design form no part of the claimed design.

1 Claim, 8 Drawing Sheets(56)
